UNITED STATES PATENT OFFICE.

ELMER A. WATTS, OF SPRINGFIELD, OHIO, ASSIGNOR TO THE MILLER IMPROVED GAS ENGINE COMPANY, OF SPRINGFIELD, OHIO, A CORPORATION OF OHIO.

BED CASTING FOR GAS ENGINES.

Application filed November 19, 1924. Serial No. 750,943.

To all whom it may concern:

Be it known that I, ELMER A. WATTS, a citizen of the United States, residing at Springfield, in the county of Clark and State of Ohio, have invented certain new and useful Improvements in Bed Castings for Gas Engines, of which the following is a specification, reference being had therein to the accompanying drawing.

10 My invention relates to internal combustion engines and in particular to an integral bed casting therefor.

It is the object of my invention to provide a single unitary integral casing in an internal combustion engine for use as the support for the cylinder valve mechanism, crank shaft, fly wheel and compressor unit, so arranged that the center of gravity will be low, the strains will be directed along the major axis of the casting, and that there will be no breakages or fracture of the parts due to strains which are not accommodated.

It is a further object to provide in a single casting all of the essential supports for all of the material portions of the engine so that the parts will be aligned and stay in alignment which is not the case when the engine is built up of a plurality of parts bolted or otherwise joined together.

30 It is a further object to provide a single casting which can be economically produced not only when it is cast but when it is machined. The casting of my invention is so designed that it may be machined in three directions simultaneously thus enabling large size engines to be produced on an economical production basis.

It is essential in such an engine which is subjected to high pressures and temperatures and which usually carries other units such as a compressor unit, that the casting be designed to take the strains along the major axis without danger of the breaking of any of the parts.

45 It is further essential to have as light weight casting as possible due to the fact that these engines are necessarily of great weight; the minimum of weight wherever possible is a great advantage.

50 It is a further object to provide a main backbone casting of the character described which has large spaces for the free circulation of cooling fluids, which is arranged to take detachable compressors and cylinder

liners, so that different sizes of cylinders and different sizes of compressors may be employed without modifying the main casting thus greatly economizing in production, as this single common unit is the base for the construction of varying capacities of engines.

It is further desirable to so construct this basic casting member that it may be one of a series of similar units which may be joined in pairs or otherwise to form unitary engines.

It is further desirable to provide in such a casting faces and supports for various types of apparatus which must be mounted upon the engine so that these kinds of apparatus may be quickly located in one position or other as may be desired.

It is further desirable to provide a casting in which the accumulation of foreign material in the water circulation passages will gravitate to a portion of the casting which may be opened up and the passages easily cleaned of this accumulation.

With these and other objects in view, the drawings illustrating this invention are as follows:

Figure 1 is a side elevation of the complete casting with the detachable bearing in place;

Figure 2 is a bottom plan view;

Figure 3 is a top plan view;

Figure 4 is a section on the line 4—4 of Figure 3;

Figure 5 is an end elevation from the valve end of the engine;

Figure 6 is an end elevation from the compressor end;

Figure 7 is a section on the line 7—7 of Figure 3, looking in the direction of the arrows;

Figure 8 is a section on the line 8—8 of Figure 3 looking in the direction of the arrows.

Referring to the drawings in detail, it will be noted that the castings distributed about the major axis 1—1 and that all moving parts also move along this major axis so that the strains are evenly distributed on the entire casting.

The casting consists broadly of four portions: an internal combustion cylinder portion, a portion for guiding the internal combustion piston and a crank and fly

wheel portion, and a portion for guiding the compressor link and piston, or cross-head.

Turning to the cylinder portion, 1 designates a cylindrical portion of the casting having an enlarged head 2 for receiving the casing 3 containing the valve mechanism as more fully set forth in my copending application Ser. No. 746,480.

10 This enlarged head 2 is provided with a series of spaced internally extending abutments or ribs 4 which are distributed about the periphery of the cylinder to act as supports for the detachable cylinder liner, the 15 other end of which is supported by the internally extending integral ring 5. An opening 6 is provided in the top of this casting 1 to which is fitted a connection. This opening permits of access to the space between the cylinder liner and the casing 1 in which cooling fluid circulates.

The second portion of the casting is designated 7. It is substantially cylindrical save for a rectangular opening 8 the purposes of 25 which will be hereinafter described.

The base of this portion 7 designated 9 is flat and is provided with the ribs 10 for supporting the slides which support the end of the piston rod to the end of the pitman connected with the crank of the main shaft of the engine upon which the fly wheel is mounted. Thus the support for the reciprocating parts is aligned with the cylinder and the crank shaft of the engine has an integral 30 support with the cylinder and with the support for the crank shaft an opening 8 permits of the ready access to these reciprocating parts for either withdrawal or renewal as well as adjustment and for the detaching 35 of the piston rod from the piston as set forth in my copending application, Ser. No. 743,431.

In furthering this idea there is provided a third portion of the engine which constitutes the support for the crank shaft, pitmen and fly wheel. A U-shaped opening is provided as at 11 for receiving the detachable bearing blocks 12 carrying the crank shaft in the aperture 13. A cap plate 14 held in position by the bolts 15 serves to support this crank shaft. The casting is broadened at this point as at 16 to form an aperture bearing and supporting surface for the crank shaft. This enlarged portion of 50 the casting also forms a housing 16 for the timing gears which are located in the space 17. It will be noted that the bearings for the crank shaft may therefore be lifted out bodily when desired without disturbing the 55 rest of the engine. The crank shaft is located approximately centrally of the mass constituting the casting. A cap can be fitted on the top of the opening 8 to enclose the fly wheel and the reciprocating parts.

60 The fourth portion of the casting is sub-

stantially cylindrical and is designated 18. It provides the upper ribs 19 and the lower ribs 20 which act as guides for the slide-block carrying the end of the compressor piston rod and the pitman. A hand hold 70 in the side of the casting as at 21 is provided for the usual purposes. The end of the casting is enlarged as at 22 for receiving the castings of the compressor cylinder so that the compressor may be detachably 75 mounted on the end of this unitary supporting casting. It will be noted also that the third portion of the casting below the crank shaft is extended downwardly in the semi-circular portion marked 23 to give the requisite clearance for the crank on the fly wheel shaft and to also provide an oil well for supplying lubrication. A casting is provided with the threaded aperture 24 from which a pipe leads for conveying the lubricant. 80

The entire casting is provided with side flanges 25, side walls 26 and 27 which are turned over to form the feet 28. A diagonally disposed transverse rib 29 is formed 90 between these side walls 25 and provided with a foot 30. This rib is so arranged as to take the thrust of the reciprocating parts. A series of transverse arch shaped ribs extending from side wall to side wall are also 95 provided such as 31, 32, 33 and 34.

On the outside of the engine there are provided a plurality of bosses or collars 35 for receiving the bolts which attach the engine bed to the usual concrete foundation. 100

On the outside of the engine bed is provided a vertical base 36 which is the outside of a casing 37 containing the valve mechanism for the engine and serving as a support therefor. 105

Referring to Figure 7, it will be noted that the casing surrounding the internal combustion engine cylinder and substantially cylindrical with exception to the lower portion which is provided with an opening at the bottom of the casing marked 37. This opening is bordered by the wall 38 on the one side and a downwardly extending apron on the other. This apron merges 110 with one of the side walls 25 of the base of the engine. A passageway marked 40 is provided from this water circulation chamber to the outside of the engine. A plate is mounted on this open mouthed passageway to normally close it, but it will be observed that any sediment or foreign material may settle to the bottom of the water circulation passageway, pass down the apron 39 and be removed through the opening 40. The engine has also formed integrally therewith the passageways 41, 42, and 43. These passageways form chambers for the introduction of air, the introduction 115 of fuel and the passage of carbureted fuel 120

- through the passageway marked 44 in Figure 5 into the valve casing whence the carbureted fuel is passed through the valve and cylinder head into the cylinder carried 5 within the portion of the casing marked 1. This manifold is therefore provided integrally with the engine so that the whole structure will contract and expand together with the minimum of joints necessary and 10 with the minimum of danger of breakage or fracture due to varying temperatures and pressures.

The top of the casting 18 is provided with 15 a rib 45 to further strengthen it along the backbone.

It will be understood that I desire to comprehend within my invention such modifications as may be necessary to adapt it to varying conditions of use.

20 Another important object of my invention is the locating of a bolt 46 beneath the portion of the casting which receives the bearing and upon which great weight and considerable thrust is placed.

25 This bolt 46 ties the two slots of the casting together, thus taking the thrust to some degree and distributing it at a point of great strain throughout the remainder of the integral bed casting.

30 Having thus fully described my invention, what I claim as new and desire to secure by Letters Patent, is:—

1. In an internal combustion engine, an integral casting consisting of an internal 35 combustion cylinder portion, a guide portion for the internal combustion piston rod, a supporting portion for the crank shaft and fly wheel, a guide portion for a compressor cylinder piston, means on said internal combustion cylinder portion for supporting a cylinder liner in spaced relation thereto, a plurality of transverse ribs, said walls and end walls integrally connecting, bracing and supporting said several portions of the casting.

2. In an internal combustion engine, an integral casting distributed about the major axis of movement of the reciprocating parts consisting of a cylinder casing portion, a 50 bed for guiding and supporting the reciprocating parts of the internal combustion piston, a portion for furnishing bearings for the crank shaft of the engine, and a portion for guiding the piston rod of a compressor attached to said engine, said casting being provided with supporting walls to form a unitary base tied together by integral ribs.

3. In an internal combustion engine, an 60 integral casting distributed about the major axis of movement of the reciprocating parts consisting of a cylinder casing portion, a bed for guiding and supporting the reciprocating parts of the internal combustion piston, a portion for furnishing bearings for the

crank shaft of the engine, a portion for guiding the piston rod of a compressor attached to said engine, said casting being provided with supporting walls to form a unitary base tied together by integral ribs, 70 a fourth portion of said ribs arched from wall to wall of the base supporting the main portion of the casting on the ground of the arch and another portion of the braces being diagonally disposed to form an abutment to take the thrust from the moving parts directly into the foundation on which the engine rests.

4. In an internal combustion engine, a unitary casting consisting of supporting side 80 walls, a cylinder casing mounted thereon, transverse ribs tying said walls and cylinder casing to one another, and a downwardly and outwardly extending apron forming a passageway for the exit of foreign material from the interior of the cylinder to the exterior of the casting, whereby the space between the cylinder casting and a cylinder liner may be drained when desired.

5. In an internal combustion engine, a unitary casting consisting of supporting side walls, a cylinder casing mounted thereon, transverse ribs tying said walls and cylinder casing to one another, a downwardly 90 and outwardly extending apron forming a passageway for the exit of foreign material from the interior of the cylinder to the exterior of the casting, whereby the space between the cylinder casting and a cylinder liner may be drained when desired, and other portions of said casting formed into chambers for use as manifolds and as supports for carburetor mechanism.

6. In an internal combustion engine, a 100 single unitary casting of substantially the same general diameter throughout, substantially equally distributed about the major axis of the engine along which the reciprocating parts have their line of movement, 110 a lateral extension midway of said casting to serve as a support for the bearings for a transverse crank to which the reciprocating parts of the engine are connected, means in said transverse portion for forming a housing and bearing support for the timing gears associated with said crank and engine, said side extension being cut away in a U-shaped aperture for receiving the detachable bearing for supporting said crank.

7. In an internal combustion engine, a single unitary casting of substantially the same general diameter throughout, substantially equally distributed about the major axis of the engine along which the reciprocating parts have their line of movement, a lateral extension midway of said casting to serve as a support for the bearings for a transverse crank to which the reciprocating parts of the engine are connected, means in 120 125 130

said transverse portion for forming a housing and bearing support for the timing gears associated with said crank and engine, said side extension being cut away in a U-shaped 5 aperture for receiving the detachable bearing for supporting said crank, and a bolt passed through said casting fore and aft beneath the U-shaped aperture for tying the walls of the casting together and for 10 operating in distributing the strain.

8. In an internal combustion engine, a single unitary casting of substantially the same general diameter throughout, substantially equally distributed about the major

axis of the engine along which the reciprocating parts have their line of movement, a lateral extension midway of said casting to serve as a support for the bearings for a transverse crank to which the reciprocating parts of the engine are connected, and a bolt located fore and aft in said lateral extension of the casting engaging the fore and aft walls thereof for tying the said walls together and distributing the strains there-through. 15

In testimony whereof, I affix my signature. 20

ELMER A. WATTS. 25
